UNITED STATES PATENT OFFICE.

JOHN MERRY, OF NEW YORK, N. Y., ASSIGNOR TO THE BIGELOW CARPET COMPANY, OF MASSACHUSETTS.

DESIGN FOR A RUG.

SPECIFICATION forming part of Design No. 30,384, dated March 21, 1899.

Application filed February 21, 1899. Serial No. 706,421. Term of patent 3½ years.

To all whom it may concern:

Be it known that I, JOHN MERRY, a subject of the Queen of Great Britain, and a resident of New York city, in the county and State of 5 New York, have invented a new and original Design for Rugs; of which the following is a specification.

My design, as shown in the drawing, consists in a new design for a rug.

10 The design is composed of a middle portion and a border.

The middle portion is rectangular in shape, made octagonal by a triangular ornamentation located at each corner of the rectangle, 15 and containing a central diamond-like figure with terminals and with surrounding bold spray-like ornamentation.

The border is composed of a narrow outer and a broad inner stripe, on both margins of 20 each of which are less conspicuous narrower stripes.

The border throughout and the middle portion, including its central and corner figures, are profusely ornamented with picturesque shapes, largely of conventional flower and 25 foliage types and distinctly suggestive of the characteristic figuring of oriental rugs.

The drawing shows one-quarter of the design, the remaining three-quarters being in all respects facsimiles thereof. 30

What I claim as new, and desire to secure by Letters Patent, is—

The design for a rug, substantially as shown and described.

In testimony whereof I have signed my 35 name to this specification in the presence of two subscribing witnesses.

JOHN MERRY.
